Primary Examiner — Susan Bennett Hattan*Assistant Examiner* — Marie D. Fast Horse(74) *Attorney, Agent, or Firm* — Fenwick & West LLP(57) **CLAIM**

We claim the ornamental design for a computing device, as shown and described.

DESCRIPTION

FIG. 1 is a top, front, and right side perspective view of a computing device;

FIG. 2 is a top, rear, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the computing device that form no part of the claimed design.

1 Claim, 8 Drawing Sheets(56)
